HINGE BRACKET

Samuel Benjinson, New York, N. Y., assignor to
Sarah Benson, New York, N. Y.

Application August 16, 1934, Serial No. 740,086

4 Claims. (Cl. 156—24)

This invention relates to hinge brackets and is particularly adaptable for use in the mounting of window shades. The same may, however, be useful for mounting other devices.

5 A principal object of the invention is to provide a hinge bracket in which the bracket arm may be readily removed from and replaced on its anchor plate.

Another principal object of the invention is to 10 construct such bracket so that the bracket arm will be held in locked position in the anchor plate, when in service, and secured against accidental removal therefrom.

Another principal object of the invention is to 15 so design the bracket arm as to provide for limitation of the swing thereof.

Another principal object of the invention is to adapt a pair of such brackets, when their arms are swung to their outward limit, to support a 20 shade roller or other device, and be thereby held in rigid condition.

Other objects will be apparent from reading this specification in connection with the accompanying drawing in which,

25 Figure 1 is a top view of a pair of brackets of the present invention supporting a window shade;

Figure 2 illustrates a bracket arm in the process of being mounted onto the anchor plate;

Figure 3 is a perspective view of a bracket arm;

30 Figure 4 is a perspective view of an anchor plate;

Figure 5 shows a modification of the anchor plate; and

Figure 6 is a modified view of the bracket arm.

35 Referring now in detail to the drawing in which similar characters refer to similar parts throughout, 10 is a bracket arm angularly bent at its hinge end to provide a bearing surface or stop 11.

40 Extending from such stop in a return bend 45 is a lip 12 cut away at its upper and lower ends as shown. These cut away portions are designated 13 and 14, respectively. The cut away portion 14 causes a hook 15 to be formed at the lower end of the lip 12.

45 An anchor plate 16 is angularly formed having a securing side 17 and a hinge side 17a. This anchor plate is slotted longitudinally intermediate its length between the securing side and hinge side thereof. Such slot is shown at 18. On the 50 securing side 17 of the anchor plate I preferably provide an extension 19 in the plane of the securing side, which extension projects into the slot 18 as shown. This form is illustrated in Figure 4, while Figure 5 shows an anchor plate 55 without such extension. Screw holes 20 extend

through the securing side of the anchor plate to facilitate the mounting of the anchor plate onto a support.

5 In service, the brackets are ordinarily used in pairs. The anchor plate 16 is secured in any convenient way to a support 21, a window sash for instance. The bracket arm is then mounted onto the anchor plate 16 by inserting first the hook 15 of the lip 12 through the slot 18 of the anchor plate, then following through the slot with the 10 remainder of the lip 12. The bracket arm is then swung outwardly until it is stopped by the bearing surface 11 contacting with the securing side of the anchor plate 16. A shade roller 22 or other device may then be mounted in the brackets 15 as shown, which will hold the brackets in their limited extended position, and form a rigid support therefor, insuring a locked relationship between the bracket arm and its cooperating anchor plate.

20 When it is desired to take down the bracket arm 10, the window shade or other device 22 is first removed in the ordinary way. Each bracket arm is then swung inwardly so that the lip 12 thereof is substantially in line with the slot 18 25 of its anchor plate. The outer end of the bracket arm 10 is then lifted so as to enable the top end of the lip portion 12 to pass out of the slot 18 and thus permit the bottom end of such lip portion, which embodies the hook 15 to clear the bottom of the slot 18 as the bracket arm is lifted from its anchor plate. In the form of anchor plate shown in Figure 4, the extension 19 guides the arcuate movement of the bracket arm in positioning the same on the anchor plate and in removing the same therefrom, and thereby results in smoother movement thereof when being affixed to or removed from the anchor plate than is the case when the form is used which is shown 30 in Figure 5, which latter form does not contain 35 the extension 19.

40 When the bracket illustrated is in service position, the hinge elements have a plurality of areas of contact with each other, which give the bracket rigid support, namely, the stop 11 bears upon the 45 securing side of the anchor plate, the edges 23, 24 of the stop bear on the inside wall of the hinge side of the anchor plate, and the lip 12 bears on the edge 25 of the slot 18. In addition, the lip 12 50 rests on the lower edge of the slot 18, while the upper edge of the lip has a bare working space from the top wall of the said slot. The result is that the brackets when used in pairs with a 55 mounting 22 between them will constitute a very rigid structure. Of course, it is understood that

the bracket arm hinge elements are designed for either right hand or left hand use.

I have illustrated and described what I believe to be the best embodiment of my invention. I do not desire to be limited, however, to the embodiment shown and described but what I desire to cover by Letters Patent is set forth in the appended claims.

I claim:

10. 1. In a bracket hinge, an anchor plate and a bracket arm, said anchor plate being bent to form a securing side and a hinge side, and slotted longitudinally thereof at its bend, said bracket arm being bent at its hinge end to form a stop, and further bent to form a hinge element, said hinge element being cut away along its upper side, and partially cut away along its lower side, whereby a locking projection is provided at its lower side, the hinge side of the anchor plate, through its slotted portion, being adapted to engage with the hinge element of the bracket arm, and upon the outward swing of the bracket arm to hold the arm in operative relation therewith.
15. 2. In a bracket hinge, an anchor plate and a bracket arm, said anchor plate being bent to form a securing side and a hinge side, and slotted
20. 25.

longitudinally of the bend, said bracket arm having a hinge end and a supporting end, and being bent at its hinge end to form a stop, and means in the bracket arm adapted to engage said anchor plate through its slotted portion, and be held in hingeable relation therewith.

3. In a bracket hinge, an anchor plate and a bracket arm, said anchor plate being bent to form a securing side and a hinge side, and slotted longitudinally of the bend, a portion of said securing side extending into the plane of the hinge side, and means in the bracket arm adapted to engage said anchor plate through its slotted portion and be held in hingeable relation therewith.

4. In a bracket hinge, an anchor plate and a bracket arm, said bracket arm being bent at one end to form a stop and further bent to form a hinge element, said hinge element with relation to said stop being stepped down at its upper side and stepped up and then down at its lower side, forming a locking projection at its lower side, said hinge element being adapted to be connected with the hinge side of said anchor plate and held in hingeable relation therewith.
